[57] CLAIM

The ornamental design for a cabinet for computer keyboard, as shown and described.

DESCRIPTION

FIG. 1 is a front perspective view of a cabinet for a computer keyboard showing our new design;

FIG. 2 is a front perspective view thereof showing a tray, forming part of the cabinet, in its extended forward position with a cabinet door folded down providing access for keying entries to a computer keyboard adapted to be supported on the tray;

FIG. 3 is a front elevational view thereof;

FIG. 4 is a left side elevational view thereof;

FIG. 5 is a bottom plan view thereof;

FIG. 6 is a right side elevational view thereof; and

FIG. 7 is a rear elevational view thereof.

FIG. 1

FIG. 2

FIG. 3

FIG. 4

FIG. 5

FIG. 6

FIG. 7
